CARTON CONSTRUCTION

Edward C. Scott, Chicago, Ill., assignor to Ace
Carton Corporation, Cicero, Ill., a corporation
of Illinois

Application July 28, 1941, Serial No. 404,280

10 Claims. (Cl. 206—59)

This invention relates to containers, and more particularly to light and economical containers for the shipping, storing, and dispensing of rolls of tape.

In the handling, shipping, and storing of rolls of tape, and particularly tape such as masking tape, decorative tinsel, and the like, which may or may not be provided with an adhesive backing, it is desirable to provide a light and simple container which permits ready access to the contents and yet provides a maximum amount of protection against injury to the outer layers of tape in case the container should be dropped or struck.

To this end, it has heretofore been proposed to provide a container having a roll-centering device adapted to be inserted in the usual large central opening in a roll of tape and retain said roll in spaced relationship with respect to the peripheral confines of the container. This manner of supporting rolls of tape prevents pressure upon or contact with the periphery of the roll, and prevents distortion or mutilation of the tape.

However, roll-centering cartons of the character above described are expensive and difficult to manufacture and ordinarily require a large number of complicated gluing and assembling operations which increase their cost in time and labor, and materially reduce the feasibility of the use of such cartons. Furthermore, the constructions heretofore proposed frequently require the securing together of several separate parts into a single unit with the manifold gluing and sealing operations thus entailed.

It is therefore an object of the present invention to provide a simple, economical, and efficient roll-centering carton of the character set forth, wherein the necessary folding, securing, and sealing operations are reduced to a minimum and a satisfactory roll-centering enclosure is provided.

Another object of the present invention is to provide a simple, compact, roll-centering carton formed from a single blank requiring a single gluing operation for its assembly and including a simple and improved means for centering the roll of tape with respect to the side walls of the carton.

It is also an object of this invention to provide a carton which may be stored or shipped flat in order to save space but which, when required for use, may readily be manipulated into roll-loading position.

Still another object of the present invention

is to provide a container construction which affords a maximum amount of protection to its contents both from physical blows and damage, and from dust and air-borne germs.

5 An additional object of the invention is to provide a single piece container blank whereby, with a single gluing operation, there is provided a roll-centering carton which may readily be folded and assembled in roll-carrying position.

10 Another feature of the present device is its utility as a combination shipping, storing and tape dispensing device, and it will be noted that the roll may be left in place on the central hub and portions removed from time to time as required for use. Access to the roll for dispensing purposes may be effected at either end of the carton merely by unfolding the desired end flap. It is therefore an object of the present invention to provide a convenient single piece tape dispensing carton of the character described.

20 Other objects and advantages will appear from a consideration of the following detailed specification. For a more complete understanding of this invention reference may now be had to the drawings, in which:

Fig. 1 is a perspective view of a container embodying the invention with one of the end flaps open;

Fig. 2 is a top plan view of the container shown in Fig. 1 with a roll of tape therein;

Fig. 3 is a vertical sectional view taken substantially along the line 3—3 of Fig. 2;

Fig. 4 is a plan view of the container blank for forming the container illustrated in Figs. 1, 2, and 3 and showing in dotted lines the position of the parts after the gluing operation and prior to completion of the assembling and loading operations;

Fig. 5 is a detailed perspective view of the interlocking flap and hub portions of the container;

Fig. 6 is a top plan view similar to Fig. 2 of another embodiment of the present invention;

Fig. 7 is a sectional view taken substantially 45 along the line 7—7 of Fig. 6;

Fig. 8 is a top plan view of the blank employed in forming the container illustrated in Figs. 6 and 7;

Fig. 9 is a top plan view similar to Fig. 2 of a third embodiment of the present invention;

Fig. 10 is a sectional view taken along the line 10—10 of Fig. 9; and

Fig. 11 is a top plan view of the blank employed in forming the container illustrated in Figs. 9 and 10.

Referring to the drawings in detail, the embodiment illustrated in Figs. 1 to 4, inclusive, comprises a blank which may be of cardboard or other suitable material. This blank is provided with laterally extending flaps and extensions, properly slit and scored or creased as indicated, so that when folded along suitable score lines it provides a substantially rectangular container. The blank includes an imperforate base or central portion 1 and oppositely disposed side and end walls 2, 3, 4 and 5 which may be folded along the score lines 6, 7, 8 and 9, respectively, to provide opposite side and end walls for the carton.

The side walls 3 and 5 may be provided with tabs 10 which are to be tucked in before the end walls are folded into place. The end walls 2 and 4 have extensions 11 and 12, respectively, forming end flaps each of which is integral with the adjacent end wall and provided with transverse score lines 13 and 14 to facilitate folding the end flap into place during the carton closing operation.

The side walls 3 and 5 are provided with extensions 15 and 16 respectively, each of which is creased along a transverse score line 17. The extension 16 is provided with a short stub 18 creased on score line 19. The extension 15 may be provided with a hub forming tongue 20, having score lines 21, 22 and 23, defining portions 24, 25 and 26.

In assembling the carton from the above described blank, the side extension 16 together with the portion 18 is first folded inwardly along the associated score line 17 to the dotted line position shown in Fig. 4. The opposite extension 15 together with the tongue 20 is then folded inwardly along the similar score line 17. When these extensions are so folded, the securing portions 18 and 26 overlap and may be secured together by gluing, stapling, or other suitable means.

After the side extensions have been secured together as aforesaid, the carton, although substantially flat and therefore in condition for storage or shipping, is ready for immediate use. The single gluing operation above recited is the only step necessary to provide a carton assembly ready to be loaded and closed.

The cartons may be opened, loaded with rolls of tape, and closed, either by hand or by suitable automatic machinery. The opening operation comprises lifting the tongue 20, thereby drawing the side walls 3 and 5 up into the position indicated by dotted lines in Fig. 3. With the tongue 20 in such raised position, the roll 27 may then be slipped into place from one end of the carton and the tongue portion 20 firmly pressed downwardly so as to contact the inner ring 28 of the roll 27 and the portion 26 is thus folded along score lines 19, 21, 22 and 23 to make the central hub or spindle upon which the roll is supported while it is in the box and about which it may rotate as tape is withdrawn from the roll and dispensed from the carton.

It will be noted that with this construction the simple act of inwardly depressing the tongue 20 forms the central hub for the roll without any additional gluing or securing step.

In Figs. 1 and 2 one of the end flaps is shown closed while the other end flap is shown open. The end flaps 11 and 12 are extensions upon the end walls 2 and 4, respectively, and, because of the transverse score line 14 on each of the end flaps, they may readily be folded and tucked into

place as illustrated. Each of the end flaps is preferably provided with suitable notches 29 or other hub portion engaging means whereby, as the end flap is tucked into place, the hub walls 18 and 24 enter the notches 29 and are rigidly retained in position thereby, as illustrated in detail in Fig. 5.

Thus it will be seen with the above embodiment that merely inserting the end flap into position causes the slots automatically to engage and secure the hub in position and lock all of the parts in a manner best adapted to resist the strains which may be imposed upon the carton. Furthermore, one end flap is always in hub supporting position during the entire tape dispensing operation.

In the embodiment of the invention illustrated in Figs. 6, 7 and 8 similar parts are designated by the same reference numerals. The tongue 20, as shown best in Fig. 8, is provided with laterally projecting portions 30 and 31 which are creased along score lines 32 and 33 and, when folded outwardly, provide additional walls for the hub of the carton as indicated in Fig. 7. With this construction the inner portion of the carton is completely enclosed, affording maximum protection to the inside of the roll, and the opening, loading and closing operations are the same as in the embodiment heretofore described. In this embodiment the inwardly projecting hub is likewise securely retained in place by the notches 29 of the end flaps 11 and 12.

In the embodiment disclosed in Figs. 9, 10 and 11, wherein similar parts are again identified by the same reference numerals, the central or base portion 1 is shown formed with a central opening 34 provided with inwardly directed flaps 35 and 36. With this arrangement the intermediate portion 25 of the hub tongue is secured in its folded position by means of the flaps 35 and 36 under which it is slipped as indicated in Fig. 10 and by which it is securely retained in place. With this arrangement the roll hub is secured at both its inner portion 25 and its outer portion to the top and bottom of the container, insuring a maximum rigidity within the limits of the characteristics of the material of which the carton is formed.

While particular embodiments of the invention have been shown, it will be understood, of course, that it is not desired that the invention be limited thereto since many modifications may be made, and it is, therefore, contemplated by the appended claims to cover any such modifications as fall within the true spirit and scope of the invention.

Having thus described the invention, what is claimed and desired to be secured by Letters Patent is:

1. A carton for enclosing and centrally supporting a roll of tape said carton comprising a single blank of material of form-retaining characteristics having a base portion defining one side of a container, a plurality of radial extensions integral with said base portion and scored to provide fold lines, portions of said extensions forming peripheral end and side walls for said carton and other portions of said extensions forming a top wall, one of said extensions having an elongated tongue and being terminally secured to another extension, said tongue being downwardly deformed to form a roll-centering hub to retain a roll against movement in any direction, and others of said extensions being in-

terengageable with the side edges of said tongue to structurally support the hub in position.

2. A roll-centering and enclosing carton comprising a base, a plurality of interlocking members extending from said base to form an enclosure, two of said members having end portions secured together and providing a roll-centering hub comprising an elongated strip of material formed and inwardly disposed so that the edges thereof form a rectangular hub spaced from the peripheral walls of said container, others of said members including securing means engaging said elongated strip to retain said hub in place.

3. In a carton having peripheral walls, a hub extension for centrally supporting rolls in spaced relationship from the peripheral walls of the carton, said hub extension comprising a substantially U-shaped strip of carton material secured to one of the carton walls and positioned intermediate the walls, and end flap means on said carton adapted to cooperate with said hub extension to retain said hub extension in a central position.

4. A one-piece blank for forming a shipping carton having a central hub portion, said blank comprising a base section forming the bottom of the carton, extensions on each side of said base section forming the side and end walls of the carton, said extensions including portions formed to interlock one with the other, one of said extensions having a tongue which may be secured to an opposed extension and displaced inwardly to form a roll centering hub, said hub being of substantially U-shape and being retained in place by others of said interlocking extensions to provide a central hub in the assembled carton.

5. A one-piece blank for forming a shipping carton having an annular interior space and a central hub portion, said blank comprising a base section having a cut-away central portion, tabs on opposed edges of said cut-away portion, side wall extensions including portions forming the top of said carton, the ends of said extensions being formed to interlock and provide a rigid structure, said extensions also including an inwardly directed hub portion engageable by said tabs on said edges of the cut-away portion.

6. A carton blank for forming a shipping and storing carton to enclose and support a roll of tape having a central opening, said blank comprising a rectangular base section to form one wall of the carton, a plurality of outwardly directed sections extending from the edges of said base section to form peripheral side walls of the carton, an opposed pair of said side walls having extensions adapted to be folded inwardly and having an elongated tongue securing said exten-

sions together to form a portion of the top wall of said carton, said extensions including a portion inwardly deformable to provide a roll centering hub in said carton, another pair of said side walls having extensions forming end flaps for said carton, said flaps being formed to interlock with the central hub of said carton.

7. A shipping carton for the support of fragile rolls without contact with the periphery of the roll comprising a base portion forming the body of the carton, walls extending upwardly from the edges of the base portion, and a top for said carton formed from extensions on said walls, one of said extensions having an elongated tongue portion supported to form an inwardly directed roll-supporting hub.

8. A one-piece blank for forming a shipping carton with a central hub portion comprising a base section forming the bottom of the carton and having a central aperture, extensions on each side of said base section forming the side and end walls of the carton, additional extensions on said side walls formed to interlock one with the other, one of said additional extensions having a tongue scored to provide inwardly directed portions connected by an intermediate portion, and means for interlocking said intermediate portion with the edges of said aperture in said base section to provide a central hub member.

9. A shipping carton for the support of rolls having central inner openings, said carton comprising a base portion forming the body of the carton, walls extending upwardly from the edges of the base portion, and extensions on said walls forming a top for said carton, two of said extensions disposed in opposed relation including portions formed and joined together to provide a rectangular hub completely enclosing the inner opening in the roll.

10. A carton for enclosing and centrally supporting a roll of tape comprising a single sheet of material having a central portion defining one side wall of a container, a plurality of opposed extensions from said central portion defining edge walls, two of said opposed extensions having inwardly extending portions secured together to also form an opposed side wall of said container, said side and edge walls forming an annulus into which a roll of tape may be inserted in edgewise relation, said annulus being of a size substantially larger than said roll of tape and said opposed side edge walls having a portion deformable into the central opening of said roll of tape to form a rectangular hub and adapted when so deformed to draw the closure more closely about said roll of tape.

EDWARD C. SCOTT.
